EMBROIDERY ATTACHMENT FOR A SEWING MACHINE OR SIMILAR ARTICLE

Donald M. Genaro, Haworth, N.J., assignor to The Singer
Company, New York, N.Y., a corporation of New Jersey

Filed Jan. 30, 1969, Ser. No. 15,565

Term of patent 14 years

Int. Cl. D15—08

U.S. Cl. D70—2

Fig.1.

Fig.2.

Fig.3.

Fig.4.

Fig.5.

Fig.6.

Fig.7.

FIG. 1 is a rear perspective view of an embroidery attachment for a sewing machine or similar article showing my new design.

FIG. 2 is a left side perspective view thereof.

FIG. 3 is a top plan view thereof.

FIG. 4 is a left side elevational view thereof.

FIG. 5 is a right side elevational view thereof.

FIG. 6 is a front elevational view thereof, and

FIG. 7 is a rear elevational view thereof.

I claim:

The ornamental design for an embroidery attachment for a sewing machine, substantially as shown.
